Primary Examiner — Katrina A Betton(74) *Attorney, Agent, or Firm* — Xiaofang Zhong; Law Office of Xiaofang Zhong, PLLC(57) **CLAIM**

The ornamental design for a ski snowboard vise, as shown and described.

DESCRIPTION

FIG. 1 is a perspective view of a ski snowboard vise showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in the drawings depict portions of the ski snowboard vise that form no part of the claimed design.
